UNITED STATES PATENT OFFICE.

LOUIS R. KRATZMUELLER, OF CHICAGO, ILLINOIS.

KNIFE AND SHIELD.

Application filed December 17, 1920. Serial No. 431,359.

To all whom it may concern:

Be it known that I, LOUIS R. KRATZMUELLER, a citizen of the United States, residing at 3510 Sheffield Avenue, Chicago, 5 in the county of Cook and State of Illinois, have invented a new and useful Improvement in Knives and Shields, of which the following is a specification.

This invention relates to surgeons' knives 10 and shields therefor, and is fully described in the following specification and shown in the accompanying drawing in which:

Fig. 1 is a front elevation of a shield with knives therein;

Fig. 2 is a rear elevation of the same;

Fig. 3 is a side elevation of a shield with a knife in place therein;

Fig. 4 is a side elevation of the shield 20 with the knife removed; and

Figs. 5 and 6 are enlarged sections on the lines 5 and 6 of Fig. 1.

In the embodiment shown the shield 10 has two clips 11, hingedly mounted thereon at one end by means of rivets 12. These 25 clips are formed as shown at 11^a in Fig. 6 to fit the rear end of a knife handle 13 which is preferably tapered as shown in Fig. 1.

The upper end of the shield 10 which is 30 of metal or the like is bifurcated and bent back upon itself forming two overlying steel portions 10^a as shown in Figs. 1 and 3. The inner end of each overlying portion 10^a is bent down at 10^b so as to lie substantially perpendicular to the main body 35 of the shield 10, and terminates in fingers 10^c which normally engage the bottom of the depression 10^d.

Plates 14 are mounted upon the upper 40 ends of the handles 13 and have necked down portions 15 which are adapted to be forced under the inclined ends 16 as shown in Fig. 5 and held in the notches 17 in the bent portions 10^b. The shield 10 is made 45 of a springy material such as tempered steel and is preferably slightly bored as shown in Fig. 4.

The method of operation is as follows:— 50 The knife handle 13 is inserted in one of the clips 11 as shown in Fig. 1 in dotted lines, and the knife is then turned until the necked down portion 15 is under the shoulder 16 and into the notch 17 as shown in Fig. 5. It will be noted that the rivets 12 55 are preferably made long enough to act as a stop for the ends of the knife handles 13.

The same operation is then followed for forcing the knife into the shield from the opposite side. The long straight fingers 10^c prevent the blades being forced into 60 contact with each other, thereby causing injury to their cutting surfaces. When the blade is snapped into place there is sufficient spring in the shield to maintain it in 65 place until it is forcibly withdrawn therefrom.

A surgeon's knife is provided, which can be readily carried in a surgeon's case or in his pocket and which is ready for use at a 70 moment's notice. With this device a surgeon can throw his knife together with the shield into the sterilizing tank without fear of injury to the cutting edges of the knife, whereas formerly it was necessary for him 75 to sterilize his knives separately necessitating the expenditure of a great deal additional time and labor.

While I have shown and described but a single embodiment of my invention, it is 80 to be understood that it is capable of many modifications. Changes, therefore, in the construction and arrangement may be made without departing from the spirit and scope of the invention as disclosed in the appended claims, in which it is my intention 85 to claim all novelty inherent in my invention as broadly as possible in view of the prior art.

What I claim as new and desire to secure 90 by Letters Patent is:

1. In combination, a knife having a rigid handle and blade, and a metal shield detachably secured to the free end of said handle and having a portion bent back over said blade, said portion being bent along a 95 line substantially at right angles to the length of said shield.

2. In combination, a knife having a rigid handle and blade, and a shield detachably secured to the free end of said handle and having a portion bent back over said blade, said portion being bent along a line substantially at right angles to the length of said shield and detachably secured to the knife 100 near the junction of said blade and handle.

3. In combination, a knife having a rigid handle and blade, a necked down portion between the handle and blade and a shield detachably secured to the free end of said handle, having a portion bent back 110 over said blade and detachably engaging said necked down portion.

4. In combination, a metal shield, a plurality of sockets hingedly attached at one end thereof, and a plurality of knives, each having a rigid handle and blade, said shield having overlying portions extending back thereover each terminating in an end portion extending toward said shield and having a notch therein, whereby one of the handles may be inserted in one of said sockets and the blade swung under the corresponding overlying portion and into engagement with said notch and means for preventing adjacent blades from touching each other.
5. In combination, a metal shield, a plurality of sockets hingedly attached at one end thereof, and a plurality of knives, each having a rigid handle and blade, said shield having overlying portions extending back thereover each terminating in an end portion extending toward said shield and having a notch therein, whereby one of the handles may be inserted in one of said sockets and the blade swung under the corresponding overlying portion and into engagement with said notch.
- 10 6. In combination, a metal shield, a plurality of sockets hingedly attached at one end thereof, and a plurality of knives, each having a rigid handle and blade, said shield having overlying portions extending back thereover each terminating in an end portion extending toward said shield and having a notch therein, whereby one of the handles may be inserted in one of said sockets and the blade swung under the corresponding overlying portion and into engagement with said notch and extensions on said end portions for preventing adjoining blades from touching each other.
- 15 20

25 may be inserted in one of said sockets and the blade swung under the corresponding overlying portion and into engagement with said notch and means for preventing adjacent blades from touching each other.

6. In combination, a metal shield, a plurality of sockets hingedly attached at one end thereof, and a plurality of knives, each having a rigid handle and blade, said shield having overlying portions extending back thereover each terminating in an end portion extending toward said shield and having a notch therein, whereby one of the handles may be inserted in one of said sockets and the blade swung under the corresponding overlying portion and into engagement with said notch and extensions on said end portions for preventing adjoining blades from touching each other.

LOUIS R. KRATZMUELLER.
